UNITED STATES PATENT OFFICE.

EDWARD S. SANDERSON, OF WATERBURY, CONNECTICUT, ASSIGNOR TO SCOVILL MANUFACTURING COMPANY, OF WATERBURY, CONNECTICUT, A CORPORATION OF CONNECTICUT.

ELECTRIC LAMP SOCKET.

Application filed October 6, 1926. Serial No. 139,822.

This invention relates to electric lamp sockets.

It is an object of the invention to provide an improved lamp socket that is effective in use and economical to manufacture.

With this object, and others, in view, the invention consists in the features, combinations, details of construction and arrangements of parts which will first be described in connection with the accompanying drawing and then more particularly pointed out.

In the drawing—

Figure 1 is a view in front elevation of a lamp socket constructed in accordance with the invention;

Figure 2 is a sectional view taken on the line 2—2 of Fig. 1; and,

Figures 3 and 4 are sectional views taken on the lines 3—3, 4—4 respectively of Fig. 2. Referring to the drawing, the lamp socket illustrated as an example comprises a shell 1, having a keyhole slot 2, and a cap 3. The shell 1 is formed, at its upper edge, with a series of equally spaced depressed portions 4 alternating with intervening ridges 5, in the nature of corrugations.

The cap 3 has a bottom flange 6 which telescopes over the upper rim of the shell. To hold the two parts of the socket against relative angular movement, the cap is provided with elements for cooperating with the corrugations of the shell. To this end, as here shown as an example, the flange 6 of the cap is provided with a series of corrugations or inward depressions 7 spaced in accordance with the corrugations of the shell. When the parts are assembled, depressions 7 fit in the corresponding depressions of the corrugated shell and this interlock holds the parts against any substantial relative angular movement.

Means is provided for locking the cap and shell together, i. e., against separating movement. As here shown as an example, the shell has a plurality of downwardly facing cut-metal shoulders 8 formed by slitting the metal in two or more depressions 4 and striking up the metal above such slits to form outward projections 9. As shown, such locking shoulders are provided in the two depressions 4 at one side of the keyhole slot

2 and a similar pair is provided diametrically opposite.

To cooperate with locking shoulders 8, the cap has a plurality of upwardly facing shoulders. As here shown as an example, the flange 6 of the cap is pierced with a series of cuts 10, parallel to the bottom edge of the flange and spaced in accordance with the corrugations of the shell. The depressions 7 above referred to are formed by pressing in the metal below the cuts 10. The depressions 7, therefore, terminate in upwardly facing cut-metal shoulders 11 some of which engage the downwardly facing shoulders 8 of the shell to hold the parts locked together.

In order to attain a firm interlock, projections 9 are extended outwardly a sufficient distance to enable shoulders 8 to take an effective and firm grip on shoulders 11 and the cap is constructed to accommodate projections 9. As here shown as an example, the flange of the cap is provided with a series of outwardly extending hoods 12. These hoods are spaced in accordance with the corrugations of the shell. As here shown, hoods 12 are formed by pressing the metal outwardly above each cut 11. When the socket parts are assembled, projections 9 are received by certain of the hoods 12 (Fig. 3) and projections 9 may be made extensive enough to give a firm interlock between their shoulders 8 and corresponding shoulders 11.

In assembled position the cap and shell are locked together by the engagement of the cut-metal shoulders 8 of the shell with the cut-metal shoulders 11 of the cap. The parts are locked against relative angular movement by the interlock of the cap corrugations 7 with the shell corrugations 4. To disassemble the parts, the shell is pressed inwardly adjacent the keyhole slot 2. This causes one pair of shoulders 8 to clear the cap shoulders. The front portion of the cap may then be tilted upwardly until the cap shoulders clear the opposite pair of shoulders 8, whereupon the cap is free to be separated from the shell. To re-assemble the parts, the cap is pressed down over the rim of the shell in any relative angular position so long as the cap corrugations

mate with the shell corrugations. By slight pressure, depressions 7 may be forced down over projections 9 until the cut-metal shoulders snap into interlocking relation, whereupon the parts are again locked.

What is claimed is:

1. In an electric lamp socket, the combination with a shell having a plurality of outwardly extending projections terminating in downwardly facing cut-metal shoulders, of a cap having a flange provided with a series of upwardly facing cut-metal shoulders and a series of outwardly extending hoods, located above said cap shoulders, for receiving said projections.

2. In an electric lamp socket, the combination with a corrugated shell having a plurality of outwardly extending projections formed in certain depressed portions of the corrugations and terminating in downwardly facing cut-metal shoulders, of a cap having a flange pierced with a series of cuts spaced in accordance with the corrugations of the shell, the metal of said flange being depressed inwardly below each cut to form

corrugations for mating with the corrugations of the shell and to form upwardly facing cut-metal shoulders for engagement with the shoulders of the shell, said flange having a series of hoods above said cuts for receiving the projections of the shell.

3. An electric lamp socket cap having a flange provided with a series of equally spaced upwardly facing shoulders, for locking engagement with downwardly facing shoulders on the socket shell, and a series of outwardly extending hoods located above said shoulders for receiving projections on the shell.

4. An electric lamp socket cap having a flange pierced with a series of equally spaced cuts substantially parallel to the bottom edge of the flange, the metal of the flange below said cuts being depressed inwardly to form locking corrugations and the metal of the flange above said cuts being struck up outwardly to form hoods.

In testimony whereof, I have hereunto set my hand.

EDWARD S. SANDERSON.
